UNITED STATES PATENT OFFICE

EDWARD KIRBY BOTTLE, OF ELMIRA, NEW YORK, ASSIGNOR TO AMERICAN SALES BOOK COMPANY, LIMITED, OF TORONTO, CANADA, A CORPORATION OF ONTARIO

CARBON CONTROLLER FOR TYPEWRITING MACHINES

Application filed November 15, 1926, Serial No. 148,361. Renewed October 22, 1930.

This invention relates to writing machines, such as typewriting machines and, with respect to its more specific features, to control an actuation of the transfer sheets in conjunction with typewriter printing mechanism of the kind which is adapted to travel, or shift over the record strips, the record strips being in superposed relation for manifolding.

One of the objects of the invention is the provision of writing machine adapted for manifold-typing long relatively superposed, paper record strips; a machine which lends itself, in a practical and efficient manner, to all the operations and manipulations required to operate on such long superposed record strips and produce a number of similar typed copies, and in which the operations of altering the typed matter on any one or all the copies are facilitated and may be speedily and efficiently accomplished.

An object specially lending itself to the foregoing object is the provision of a simple and practical device wherewith the actuation and positioning of the transfer sheets—especially a large number of relatively superposed transfer sheets—is rendered easy and convenient, so that underlying record strips may be exposed for inspection and correction while the transfer sheets remain in their sequence of superposition relative to the record strips.

Another object is the provision of a writing machine of the character referred in which all of the superposed transfer sheets for transferring inscription from one record strip to another are caused to lie in relatively taut condition between and crosswise of the record strips; slackness and consequent wrinkles thereof between the record strips being largely eliminated.

Another object is the provision of a practical device for attaining the objects above mentioned, together with the feeding of the transfer sheets for supplying fresh transfer surface to the printing point.

Another object is the provision of a practical device for attaining the above objects, in which the action of the parts is so controlled that the transfer relation between the record strips and the transfer sheets will be

assured, largely without the attention of the operator.

Other objects of the invention will in part be obvious and will in part appear herein-after.

The invention accordingly comprises the features of construction, combinations of elements, and arrangements of parts, which will be exemplified in the construction hereinafter set forth and the scope of the application of which will be indicated in the claims.

For a fuller understanding of the nature and objects of the invention reference should be had to the following detailed description taken in connection with the accompanying drawings, in which:

Fig. 1 is a side elevation of a writing machine embodying the invention, certain parts being omitted for clearness of illustration.

Fig. 2 is a plan of Fig. 1, the typing mechanism and certain other details being omitted.

Fig. 3 is a plan view, similar to Fig. 2, both the typing mechanism and the carriage therefor being omitted, and some modification of parts being illustrated.

Fig. 4 is a side elevation of Fig. 3, and diagrammatically showing the strip clamping jaw actuating mechanism.

Fig. 5 is a transverse section of Fig. 3 on line 5—5.

Fig. 6 is a transverse section of Fig. 3 on line 6—6.

Fig. 7 is a transverse section of Fig. 3 on line 7—7.

Fig. 8 illustrates a part length of each record strip.

Fig. 9 is a perspective view of a transfer strip core.

Fig. 10 is a perspective view of a modified form of transfer strip holder, also appearing at one side of Fig. 2.

Fig. 11 is a perspective fragmentary view, partly in section, showing the transfer-sheet slack take-up device, which may be associated with the arrangement shown in Figs. 1 to 5, inclusive.

Fig. 12 is a detail.

Referring more specifically to the drawings, the platen of the writing machine is indicated at 1, (Fig. 3) being disposed be-

tween the parallel side bars 2 of the frame of the machine, the frame including legs 3 suitable in number for supporting the platen at a convenient height for the operator.

Opposite the advance end of the platen is a clamping jaw 4 which, by a suitable pedal 51, and operative connections therefrom to said clamping jaw, such as the link 52, and levers 53 and 54, and spring 55, may be caused to cooperate with the platen to grip and release the record strips at such point. The record strips, in superposed relation, advance to position over the platen where they may be operated upon by the printing mechanism of the machine. A large number of record strips in superposed relation may be employed. For the purpose of illustration, three record strips, 5, 6, and 7, are shown. In Fig. 3 these strips are shown broken away. These strips may come from any suitable source of supply, and each strip has a longitudinal series of printed forms and weakened lines between successive forms, the forms on one strip being adapted to register in superposed relation with those on the other, so that printing upon the uppermost strip will be transferred to the lower strip in the same relation in the printed forms. A part length of one of the printed strips on a reduced scale is shown in Fig. 8, the weakened lines being indicated at 56. To feed the record strips, the clamp 4 may be lifted by operation of the pedal, the superposed strips grasped by the operator and drawn across the platen so as to bring the next succeeding set of printed forms into inscribing position on the platen. Thereupon the clamp 4 will be permitted to resume its grip on the strips. This clamp will hold the strips tightly so that the previously inscribed sections of the strip may be torn off along the straight edge provided by the clamp or along the weakened lines, which latter are in registry when the forms are.

The numerals 8 and 9 indicate two transfer sheets, the sheet 8 lying between the two uppermost record strips, and the sheet 9 lying between the two lower record strips. These transfer sheets are adapted to transfer printing impression from the topmost record strip to those below, and may be of usual transfer material as, for instance, the well-known "carbon" transfer sheets of paper. The numerals 10 indicate a pair of parallel guide, guide-rods or bars, rotatably supported along side the path of the record strips. These guide-bars are similar to each other and are similarly supported on the frame of the machine, so that description of one will suffice for both. The numerals 12 and 13 indicate brackets bolted to the outside of the frame members 2 and providing bearings in which the guide-bars 10 are journaled. The bracket 12 has a pivoted jaw 14 which is adapted to cooperate with an annular groove in the rod 10 to hold said rod from longitudinal

movement. A spring 15 is utilized to retain jaw 14 in cooperative relation to the rod 10. The bracket 13 carries a split block 16, each section of which is suitably shaped to provide a bearing surface 17 for the cylindrical end 18 of the guide-rod 10. A thumb screw 19 serves to regulate the grip of the bearing surfaces on the guide-rod, so that the resistance to rotation of the guide-rod may be regulated, or the guide-rod held from rotation, as desired. The guide-rod has a knurled head to facilitate its convenient rotation. The guide-bars 10 are thus removably connected to the frame of the machine. It will be understood that the above description applies equally to Figs. 1 to 5, inclusive.

Longitudinally slideable on the guide-rods 10, so as to be reciprocally shiftable lengthwise relative to the record strips, are the transfer sheet holders 20 which, in the embodiment of Figs. 3, 4, and 5, include a pair of cylindrical cores made of wood, one core for each rod, the length of each core being equal to the width of a transfer sheet. The cores are indicated in dotted lines in Fig. 3. Each of the transfer sheets is coiled around and held on the two cores and is adapted to unwind from one core and extend therefrom into transfer relation to the record strips, crosswise of the direction of advance of such strips, as clearly illustrated in Fig. 5. In the embodiment illustrated in Figs. 3, 4, or 5, rotation of either of one of the guide-rods is intended to effect rotation of the core 20 thereon and consequent feed movement of the transfer strips from the other core, for the purpose of bringing fresh transfer surface to the printing point. The rods 10 may be rotated in either direction. The axial-bearing opening 57 through the cores is made angular in shape, and the cross section of the bars 10 is similarly angular, so that rotation of either of said bars will effect rotation of its core 20, the cores nevertheless being adapted to be reciprocally shifted longitudinally of the guide-bars, when desired.

For the purpose of shifting the cores 20, a manually operable, reciprocal, shift-frame may be provided, and may include two shiftable yokes of similar construction, each core being preferably detachable from its yoke. Each yoke is adapted to act as a core-shifter and comprises a neck 21 and two arms 22 and 23, between which arms the core 20 is interposed. The arm 23 of the shiftable yoke comprises two bearing jaws 24 and 25 (Fig. 5), the jaw 24 being pivoted at 26 to the jaw 25. The bearing provided by the cooperative jaws 24 and 25 is sufficiently large to permit rotation of the angular guide-bar relative to the yoke within the bearing and supports the yoke as it is shifted or slid longitudinally in either of opposite directions along said guide-bar. For holding the bearing jaws 24 and 25 in closed position, a latch 27 carried

by arm 23 is adapted to engage a tooth 28 on the bearing jaw 24. By withdrawing the latch by its handle 29 against the resistance of spring 30, the jaw 24 may be rotated to 5 permit mounting and demounting of the yoke on the guide-bar 10.

The neck 21 of the yoke comprises a rod adjustably connected to the arm 23 in a manner to permit the distance between the arms 10 22 and 23 to be varied so as to adjust the width of the yoke. As illustrated, one end 31 of rod 21 is of angular cross-section so as to enter and fit a counter-part angular aperture 32, in the arm 23. Threads on the end 15 31 receive the nuts 33 for holding the rod 21 in adjusted position on arm 23.

Washers 34 and 35 are interposed between the ends of cores 20 and the yoke arms 22 and 23. These washers are shiftable on the 20 guide-rods 10, which pass through angular bearings opening therein, and the washers also serve as gauges for the opposite edges of the transfer sheets where wound on the cores. It will be seen that, when the yokes 25 are shifted longitudinally on the guide-rods, positive shift of the cores therewith is effected, the washers protecting the edges of the transfer sheets from injury by direct contact with the yoke arms.

30 In order that the two transfer sheet holders 20 may be shifted in a uniform manner, they are connected for shifting together. To effect this the shiftable yokes hereinbefore described are joined across the machine beneath the platen 1, by a strong and rigid shifter bar 36, which is a part of the shift frame. As illustrated, the bar 36 is integral with the two yoke arms 23, and is bent at 37 to underlie the side frame members 2 and 40 may have the upturned part 38, better to escape the knees of the operator. The yoke arms 23 have elongated bearings as at 40 provided by the jaws 24 and 25, which closely fit around the corners of the angular guide-rods 10, and relative to which the guide-rods 10 may rotate. By this construction, simultaneous shift of both yokes is effected by manually shifting either, or by shifting the shifter bar 36, with consequent simultaneous shift of both holders, or cores 20. It 45 will be seen that the points of attachment of the transfer sheets to the shift frame, through the cores and yokes, are respectively adjacent each of opposite sides of the record strips, so as to readily permit the transfer sheets to enter between the record strips.

In order to minimize chance of the transfer sheets being shifted into position to be gripped by the clamp 4, the extent of their 50 shift toward the advance end of the platen may be limited so that the ultimate extent of shift will not be sufficient to carry the transfer sheets into gripping relation with said clamp. To this end the rods 10 may each be 55 provided with yoke stops 39 longitudinally

adjustable on said rods, and against which the bearings 40 of the yoke arms 23 are adapted to abut, to arrest the transfer sheets short of the clamp 4.

In the form illustrated in Fig. 3, the transfer sheets are wound upon cores 20, of which there is one at each side of the path of the record strips. A plurality of the transfer sheets, in superposed relation to each other, are rolled into a coil at one end, on one of the cores, one end of the assemblage being held on the core by suitable spring clips. The free ends of the sheets are then drawn across the platen and attached to the core 20 at the other side, so that, when the latter core is rotated by 70 rotating its guide rod 10, the transfer sheets will be drawn from one core and wound up on the other, as will be readily understood. It will be perceived that the transfer sheets lie between superposed record strips, so that the 75 path of one of the sheets from core to core is longer than that of the other. In the embodiment illustrated, the path of the topmost transfer sheet is the longer, and this sheet acts as a driver and is tautened from core to core 80 by the drawing operation. The underlying transfer sheet, however, has a shorter path, and the drawing operation results in the production of slack in the underlying transfer sheet, which slack may result in buckling, or 85 loose condition thereof between the record strips, so as to interfere with efficient manifold inscription thereby. Suitable provision is made for tautening the underlying transfer sheet where it lies between the record strips 90 and, preferably, the means for doing so is made shiftable with the transfer sheets. In the embodiment illustrated, referring to Fig. 11, the underlying transfer sheet 9, and all the other underlying transfer sheets, if more than 95 two are employed, are pressed by a weighted roller 60, which is adapted freely to gravitate in guideways 61 in the upstanding arms 62 of a U shaped frame, the cross piece of which is indicated at 63, this U shaped frame being removably fixed to the side face of the shifter frame 36, between one of the cores 20 and the adjacent record strips. The weighted rollers 60 are independent of each other and rest 100 freely upon the underlying transfer sheets 100 and freely gravitate downwardly in the guideways 61. These rollers 60 may be introduced at the top of the guideways 61, or they may be introduced laterally of the transfer sheets upon removal of the keeper plates 64, which 105 latter are removably attached to the outside faces of the arms 62 and serve laterally to close the guideways and to retain the weighted rollers.

Referring to Fig. 3, it is to be understood 110 that the U shaped frame 62 is to be mounted on the shifter frame 36 between the side bar 2 and the adjacent core 20. For lack of illustrative space in Fig. 3, the slack take-up is 115 separately illustrated in Fig. 11. The slack 120

take-up device may be duplicated on the opposite side of the machine, if desired. As the underlying transfer sheets are delivered from the coil, the rollers 60 take up the slack 5 so that such sheets lie in flat and fairly taut condition between the record strips.

Instead of rotating one of the cores 20 to draw the superposed transfer sheets across the platen, provision may be made whereby 10 they may be conveniently drawn by hand from one of the coils. To this end the wing nut 19 may be screwed up tightly to prevent rotation of one of the guide rods 10, as, for instance, the guide rod illustrated at the 15 upper part of Fig. 2. Thereupon, a rod or bar 65 may be utilized simultaneously to grip all the transfer sheets against the surface of the core. In this case, however, it is preferred to flatten the surface of the core 20 as illustrated at 66 in Fig. 10, so that the bar 65 may effectively grip the transfer sheets throughout their width. The bar 65 may enter slots 67 and 68 in the washer 35 and arm 23, respectively, so as to be removably 25 held in position. A tight fitting of the bar 65 in the slots will be sufficient to cause the bar to firmly grip the transfer sheets and hold them in place. By raising the bar 65, grip on the transfer sheets will be relieved. 30 Thereupon the transfer sheets may be grasped by the hand and drawn from the coil on the opposite side so as to bring fresh transfer material over the platen. It will be noted, also, that each transfer sheet may be 35 separately manipulated and tensioned across the platen so as to avoid slack. The bar 65 may have a straight edge 68 adjacent the transfer sheets, so as to provide a tearing bar, against which the transfer sheets may 40 be readily torn, and the used portions thus removed. It will be noted that the bar 65, like the core 20, is shiftable with the transfer sheets and with the shift frame 36.

The typewriting mechanism is indicated 45 generally by the numeral 70. This consists of a typewriter which is shiftable over the platen 1, both in line spacing and letter spacing directions. The illustration herein of the typewriter is largely diagrammatic, it being 50 sufficient to say that it is a regularly operating typewriting machine shiftable as stated, and it may be similar to the shiftable printing mechanism commonly employed in typewriting machines having a large relatively stationary, flat platen, such as the platen 55 1 referred to herein. An example of such a typewriting machine is found in the Elliott-Fisher billing machine, which is commonly used. The shiftable typewriting machine 60 has the usual inking ribbon, which shifts with the typewriting machine both in line spacing and in letter spacing directions, the type of such machine striking against the ribbon, which ribbon is thus pressed against 65 the uppermost record strip and gives the in-

scription on the top record strip. It will thus be seen that the typewriter ribbon acts as a transfer sheet and that it is independent of the other transfer sheets, 8 and 9. In Fig. 1 the inking ribbon is diagrammatically illustrated at 71 and a striking type at 72, it being understood that suitable guides on the typewriting machine support the ribbon in position opposite the printing point, where struck by the type. Supporting the printing mechanism, and practically forming a part of the frame thereof, is a carriage which is reciprocally shiftable over the relatively superposed record strips. In its main construction the carriage is of the form commonly employed in the Elliott-Fisher billing machine, and includes the front and rear parallel bars 75 and 76 joined by the parallel longitudinally extending bars 77 and 78, to form a rigid rectangular frame through the 80 opening in which the record strips are exposed, and may be reached by the printing mechanism of the typewriter. On the front bar 75 of the carriage are rollers 79, which rest upon the side frames 2 and support the carriage at the front, the side frames 2 acting as tracks. At the rear are the large rollers 80 and 81 journaled on a shaft 82 supported in brackets extending rearwardly of the carriage. At the outer sides of the rollers 80 and 81 are the pinions 83 and 84 fixed to the shaft 82, and engaging racks 85 and 86, fastened to the adjacent side frames 2. Fixed to rotate with the shaft 82 is the finely toothed ratchet wheel 87. The numeral 88 indicates a pawl having several teeth adapted to cooperate to engage the teeth of the ratchet wheel and rotate the latter. The pawl 88 is pivoted to an intermediate pawl arm 89 oscillatably mounted concentrically with the shaft 82. The arm 89 is stressed to rearward position by a spring 90, so that the pawl 88 lies against a stop pin 91. By rotating the pawl arm 89 to the left, Fig. 1, the pawl 88 will cooperate to rotate the ratchet wheel 87 and thereby rotate the pinions 83 and 84, so as to shift the carriage to the left, relative to the platen, the direction of shift in the embodiment illustrated being for line spacing. For actuating the pawl arm 89 to effect 100 shifting, it is operatively coupled with an oscillatory rod 92 mounted on the side of the carriage and extending to the front, where it is provided with a handle 93 for manually actuating the same. Fixed to rod 92 is a 105 cam arm 120 which lifts a gravitatively movable plunger 121 to in turn contact with and move a projection 122 of an arm 123 journaled on shaft 82. The retracting spring 90 is connected to arm 123, as shown in Fig. 1. 110 Arm 123 has a pin 124 engaging a slot in pawl 88. By rotating the handle 93 in one direction the carriage is caused to shift until the arm 123 is arrested by the stop 94. Upon 115 releasing the handle 93, the arms 89 and 123 120

and pawl 88 are retracted, ready for again rotating the ratchet wheel 87 in line spacing direction. It will be observed, however, that the carriage frame may be grasped and moved back and forth at will in line spacing direction, when the pawl 88 is out of engagement with the ratchet wheel. The ratchet wheel and its actuating members, including the handle 93, are for the purpose of progressively 10 advancing the carriage in line spacing direction, line by line, as it were. The detail shifting mechanism for the carriage just described is similar to that employed in the Elliott-Fisher billing machine to which reference has 15 been made.

On the carriage rests the typewriting machine 70, being supported at the front by the rollers 94 resting on the bar 75, and being supported at the rear by the rollers 95 resting 20 on the bar 76, the typewriting machine being held against movement in line spacing direction relative to the carriage, but being reciprocally shiftable on the carriage in letter spacing direction, in the present embodiment, and as exhibited in the Elliott-Fisher 25 billing machine aforesaid.

Depending from the bar 76, or lateral extensions thereof, are devices which are adapted to be moved into and out of position to 30 cause shift movement of the transfer sheets 8 and 9 in line-spacing direction, with the carriage. In the embodiment illustrated this means consists of a dog, or dogs, 100 (Fig. 1) pivoted to brackets 101, which 35 brackets are removably attached at opposite ends of the bar 76. When in lowered position, as illustrated in Fig. 1, the dogs 100 are adapted to contact with the yoke arms 22 of the shiftable frame, and thereby shift said 40 frame and the transfer sheets carried thereby, in line-spacing direction. In the embodiment illustrated in Figs. 1 to 5, inclusive, shift of the carriage toward the left, Figs. 1 and 2, causes shift of the shift frame by 45 the dogs coming into contact with the arms 22 and thereafter pressing the shift frame to the left, the carriage being freely shiftable to the right independently of the shift frame. When desired, however, the arms 22 may be 50 provided with a retainer arm 102, Fig. 12, pivoted to the arm 22 and movable into and out of position opposite the dog 100, so that as the carriage shifts to the right, Fig. 2, the shift frame will move therewith.

55 To arrange the machine for operation, the printing mechanism 70 will be shifted rearwardly, and the several record strips drawn from their supply into position over the platen 1, the lowermost record strip lying on the platen. Thereupon, the other record strips will be thrown back and the lowermost transfer sheet laid in position on the lowermost record strip. Then the other record strips are replaced in succession over the 60 placed transfer sheet, and interleaved with

the other transfer sheets, as will be understood. Then the free ends of the transfer sheets are attached to the core at the opposite side of the machine, being drawn as taut and smooth as desired. The advance ends 70 of the record strips are then laid under the clamp jaw 4. The machine is then ready for typing the record strips. The printing mechanism may be shifted longitudinally of the platen by shifting the carriage, and crosswise of the platen by shifting the printing mechanism on and relative to the carriage. It will be understood that the crosswise shifting of the printing mechanism may be accomplished either by hand or by the letter 75 spacing key of the typewriter, as usual in machines of the type herein referred to, and exemplified in the Elliott-Fisher billing machine.

80 Printing on the topmost record strip will be transferred to the underlying record strips by the interposed transfer sheets. Typing having been completed, the pedal 51 may be actuated to relieve the clamp 4 from grip on the record strips and the latter may be 85 grasped by the operator and drawn longitudinally along the platen so as to bring succeeding printed forms into position on the platen, all without disturbing the transfer sheets. However, should it be desired to 90 alter or correct the typed inscription at any point, the printing mechanism may be shifted rearwardly a sufficient amount, and the transfer sheets may also be shifted to position uncovering transferred impression on the underlying record strips. Then, by freeing the record strips from the front clamp 4, they 95 may be lifted and thrown back at will, so as to expose the transferred impression on any one of them, and correction may conveniently 100 be made as desired. It will be noted that the shifting of the transfer sheets does not disturb their sequence of superposition relative to the record strips. On the contrary, their 105 relative sequence is maintained the same as originally. Furthermore, it will be noted that neither the mounting nor the sequence of position of the record strips need be disturbed in order to make alterations or corrections. In consequence, after the transferred 110 impression has been altered, the record strips may be restored to superposition, and this superposition will be the same as before, with the several transferred inscriptions in superposed registry with each other. Thereupon, 115 the shift frame may be actuated to return the transfer sheets to position required for manfolding impression, as before. It will be seen, therefore, that corrections, alterations, additions, and the like, may be applied to the 120 underlying record strips, while maintaining superposed interleaved arrangement of the transfer sheets, and without detaching the transfer sheets at either side of the platen.

125 When a transfer sheet is sufficiently wide to 130

cover the usual writing space, it may be unnecessary to shift the underlying transfer sheets in order to cover additional space to receive original impression. Should the transfer sheet be relatively narrow, as, for instance, illustrated in Fig. 3, and it be desired to manifold impression at the left of the transfer sheet shown in said figure, the dogs 100 will come into contact with the yoke arm 22, before the printing point has reached the edge 105 of said transfer sheets, and thereafter said transfer sheets will be shifted with the printing mechanism as the latter shifts in line spacing direction. When desired, the dogs 100 may be readily turned upwardly and held out of position for effecting shift of the underlying transfer sheets by the carriage. Inasmuch as the edges 105 of the transfer sheets shift toward position underlying clamping jaw 4, it is intended that the bearings 40 shall contact with the stops 39 before this happens. This arrest of the shifting of the transfer sheets will prevent clamping of the transfer sheets by the clamp 4 and avoid tearing of such sheets when the shift frame is moved in the opposite direction. It will be noted that when the transfer sheets 8 and 9 and the printing mechanism are in relative position to manifold printing impression, the ink ribbon transfer sheet 71 is in superposed relation to the transfer sheets 8 and 9, which underlie record strips, and it will be further noted that, notwithstanding that the ink ribbon transfer sheet is independent of the other transfer sheets, and at times is shifted independently of the latter, nevertheless, provision is hereby made for maintaining superposed relation between the ink ribbon transfer sheet and the other transfer sheets during shift of the ink ribbon transfer sheet in line spacing direction.

By the provision of the slack take-up means, the underlying transfer sheets, though uncoiling from one core and coiling on the other, are nevertheless kept taut and smooth between the record strips. As explained in connection with the flat-faced core illustrated in Figs. 2 and 10, the underlying transfer sheets may be drawn from one core by hand so that all shall lie in smooth, taut condition between the record strips, the bar 65 affording means for tearing off used portions of the transfer sheets. Inasmuch as the cores 20 are separate from the washers 34 and 35, and inasmuch as the yokes are adjustable in width through the instrumentality of the nuts 33, it will be seen that the machine is adapted to accommodate transfer sheets of several different widths.

It will be noted that in each modification the transfer sheets 8 and 9 are so connected to the shift frame that it always remains in flat manifolding condition between its points of attachment to the frame, whether shifted in one direction or the other. The cores 20 serve

to brace the transfer sheets widthwise and take the pressure of shifting. Also the tearing bar 65 coacts with the adjacent core to brace the transfer sheets widthwise. Thus there need be practically no crumpling of the transfer sheets 8 and 9 during their shift movements.

Since certain changes may be made in the above construction, and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. In a writing machine, in combination, a transfer sheet disposed and adapted to transfer to one record strip printing impression made on a relatively superposed record strip, said transfer sheet being mounted for being shifted relative to said strips into positions, respectively, covering and uncovering transferred impression while maintaining its sequence of superposition relative to said record strips, a strip clamping jaw movable into and out of position for holding the strips, and means adapted to limit the extent of shift movement of said transfer sheet toward said jaw.

2. In a writing machine, in combination, a plurality of relatively superposed transfer sheets rolled into a coil at one end, a member movable to effect simultaneous drawing of the transfer sheets between relatively superposed record strips and while in relatively superposed relation, one of said transfer sheets at its other end being movable synchronously with said member as said member makes drawing movement, and means adapted to cooperate to taunt another one of said transfer sheets where it lies between the record strips.

3. In a writing machine, in combination, a plurality of relatively superposed transfer sheets rolled into a coil at one end, a member movable to effect simultaneous drawing of the transfer sheets between relatively superposed record strips and while in relatively superposed relation, one of said transfer sheets at its other end being movable synchronously with said member as said member makes drawing movement, and means adapted to cooperate to taunt another one of said transfer sheets where it lies between the record strips, said coil and member being mounted for movement to carry said transfer sheets

into positions, respectively, covering and uncovering transferred impression while maintaining their sequence of superposition relative to said record strips.

- 5 4. In a writing machine, in combination, a plurality of relatively superposed transfer sheets rolled into a coil at one end, a member movable to effect simultaneous drawing of the transfer sheets between relatively superposed record strips and while in relatively superposed relation, one of said transfer sheets at its other end being movable synchronously with said member as said member makes drawing movement, and means adapted to cooperate to tauten another one of said transfer sheets where it lies between the record strips, printing mechanism shiftable relative to the record strips in line-spacing and in letter-spacing directions, respectively, a transfer sheet, independent of said coiled sheets, shiftable with said printing mechanism in each said direction, said coiled transfer sheets being adapted to shift with said printing mechanism in one said direction.
- 10 5. In a writing machine, in combination, a plurality of relatively superposed transfer sheets rolled into a coil at one end, a member movable to effect simultaneous drawing of the transfer sheets between relatively superposed record strips and while in relatively superposed relation, one of said transfer sheets at its other end being movable synchronously with said member as said member makes drawing movement, and means adapted to cooperate to tauten another one of said transfer sheets where it lies between the record strips, printing mechanism shiftable relative to the record strips in line-spacing and in letter-spacing directions, respectively, a transfer sheet, independent of said coiled sheets, shiftable with said printing mechanism in each said direction, said coiled transfer sheets being adapted to shift with said printing mechanism in one said direction, and into and out of positions, respectively, covering and uncovering transferred impression while each maintains its sequence of superposition relative to said record strips.
- 15 6. In a writing machine, in combination, a transfer sheet disposed and adapted to transfer to one record strip printing impression made on a relatively superposed record strip, and a manually operable reciprocal frame to which said transfer sheet is attached adjacent each of opposite sides of the record strips for bodily reciprocal movement relative to said record strips while maintaining its sequence of superposition relative to said record strips, said frame extending beneath the platen between the points of attachment of said transfer sheet thereto.
- 20 7. In a writing machine, in combination, a transfer sheet disposed and adapted to transfer to one record strip printing impression made on a relatively superposed record strip,

a manually operable frame reciprocal to shift said transfer sheet relative to the record strips while maintaining the sequence of superposition of said sheet relative to said strips, a rotatable core from which said transfer sheet unwinds and extends into transfer relation to the record strips, said core being reciprocally shiftable with said frame, means for detachably attaching the free end of said transfer sheet to said frame so as to shift therewith, and a tearing bar adjacent said attaching means.

8. In a writing machine, in combination, a carriage reciprocally shiftable over relatively superposed record strips, printing mechanism reciprocally shiftable on said carriage, a transfer sheet disposed and adapted to transfer to one of said record strips printing impression made on another, a reciprocal frame to which said transfer sheet is attached for bodily reciprocal movement relative to said record strips, and means adapted to be moved into and out of position to cause shift movement of said carriage to be imparted to said frame.

9. In a writing machine, in combination, a plurality of relatively superposed transfer sheets rolled into a coil at one end, a member movable to effect simultaneous drawing of the transfer sheets between relatively superposed record strips and while in relatively superposed relation, one of said transfer sheets at its other end being movable synchronously with said member as said member makes drawing movement, a frame reciprocal to shift said coil and member bodily relative to said record strips, and means, shiftable with said frame, adapted to cooperate to tauten another one of said transfer sheets where it lies between the record strips.

10. In a writing machine, in combination, a platen, printing mechanism, a transfer sheet holding device, said printing mechanism and said holding device each mounted for being manually shifted, one independently of the other, in either of the same opposite directions and longitudinally of said platen, said printing mechanism, also, mounted for being manually shifted cross-wise of said platen in either of opposite directions at right angles to the directions of shift of said holding device, and a member adapted, at will, to be set to cause shift of said holding device by shift of said printing mechanism in one of said opposite directions of longitudinal shift, said printing mechanism being shiftable in the opposite longitudinal direction independently of said holding device.

11. In a typewriting machine, in combination, a platen over which superposed record strips advance to position for inscription, and holders for a transfer sheet which extends between the record strips cross-wise of the direction of advance of the record strips, said holders being reciprocally shiftable length-

wise of the record strips so as to shift the transfer sheet to position uncovering inscription on the underlying record strip, a jaw adapted to cooperate to grip and release the record strips at the advance end of said platen, means to operate said jaw, and means adapted to limit the extent of that shift movement of said holders which shifts said transfer sheet toward said gripped portions of said record strips.

12. In a typewriting machine, in combination, a platen over which superposed record strips advance to position for inscription, and holders for a transfer sheet which extends between the record strips cross-wise of the direction of advance of the record strips, said holders being reciprocally shiftable lengthwise of the record strips so as to shift the transfer sheet to position uncovering inscription on the underlying record strip, a jaw adapted to cooperate to grip and release the record strips at the advance end of said platen, means to operate said jaw, means adapted to limit the extent of that shift movement of said holders which shifts said transfer sheet toward said gripped positions of said record strips, printing mechanism shiftable lengthwise of the record strips and means adapted to limit the extent of shift of said printing mechanism.

13. In a typewriting machine, in combination, a pair of reciprocally shiftable transfer-sheet holders positioned at opposite sides of the longitudinal path of movement of the record strips between which holders the transfer-sheet extends transversely across the record strips into transfer relation therewith, a connection from one holder to the other for causing shift movement of one simultaneously with that of the other and printing mechanism shiftable independently of said holders and in line spacing and letter spacing directions.

14. In a typewriting machine, in combination, devices for supporting a transfer-sheet for shift movement relative to the record strips including a rotatably mounted guide-rod, a transfer-sheet holding core longitudinally slidable on said rod and connected to rotate therewith, a core shifter longitudinally shiftable on said rod and relative to which said rod rotates, and means for engaging said shifter with said core for positive shift of said core with said shifter in either of opposite directions.

15. In a typewriting machine, in combination, devices for supporting a transfer-sheet for shift movement relative to the record strips including a pair of rotatably mounted guide-rods, transfer-sheet holding cores, one on each rod, longitudinally slidable on said rods and connected to rotate therewith, respectively, core-shifters, one on each rod and longitudinally shiftable on said rods, said rods being rotatable relative to said shifters,

means for engaging each shifter with its respective core for positive shift of said cores with said shifters in either of opposite directions, and a shifter bar to which each of said core shifters is connected for being simultaneously shifted.

16. In a typewriting machine, in combination, devices for supporting a transfer-sheet for shift movement relative to the record strips including a transfer-sheet holder, a guide by which said holder is supported for shift movement, and a shifter yoke, said holder being engaged between the arms of said yoke.

17. In a typewriting machine, in combination, devices for supporting a transfer-sheet for shift movement relative to the record strips including a guide-rod, a shifter yoke slidable along said rod, one arm of said yoke having pivotally connected bearing jaws between which said rod is adapted to pass, means, including a latch on said yoke for holding said jaws closed, and a transfer-sheet holder engaged between the arms of said yoke and slidable therewith.

18. In a typewriting machine, in combination, devices for supporting a transfer-sheet for shift movement relative to the record strips including a guide-rod, a shifter yoke slidable along said rod, one arm of said yoke having pivotally connected bearing jaws between which said rod is adapted to pass, means including a latch on said yoke for holding said jaws closed, and a transfer-sheet holder engaged between the arms of said yoke and slidable therewith, the neck of said yoke comprising a rod so adjustably connected to the arm having said bearing jaws as to permit adjustment of the width of the yoke.

19. In a typewriting machine, in combination, a guide-rod of angular cross-section, rotatably supported alongside the path of the record strips, a transfer-sheet holding core longitudinally slidable on said rod having an angular bearing opening engaged by said rod, core engaging means comprising a yoke having an arm in which said rod is adapted to rotate, said arm comprising separable parts adapted to open and close to permit mounting and demounting of said yoke, and means adapted to hold said separable parts in position to retain the yoke on said bar.

20. In a typewriting machine, in combination, a stationary frame, a platen over which superposed record strips are adapted to lie in position for inscription, devices for supporting a transfer-sheet for shift movement relative to the record strips including, rotatable, parallel, guide-rods supported by said frame, one at each side of the record strips, transfer-sheet holding cores rotatable with said rods, one shiftably mounted on each of said rods, core-shifting yokes, one slidably mounted on each of said rods, and a shifter

bar to which each of said yokes is connected for being simultaneously shifted.

21. In a typewriting machine, in combination, a stationary frame, a platen over which superposed record strips are adapted to lie in position for inscription, devices for supporting a transfer-sheet for shift movement relative to the record strips including, rotatable, parallel, guide-rods supported by said frame, one at each side of the record strips, transfer-sheet holding cores rotatable with said rods, one shiftably mounted on each of said rods, core-shifting yokes, one slidably mounted on each of said rods, and a shifter bar to which each of said yokes is connected for being simultaneously shifted, said rods being removably connected to said frame, and said yokes being removably mounted on said rods.

22. In a typewriting machine, in combination, a stationary frame, a platen over which superposed record strips are adapted to lie in position for inscription, devices for supporting a transfer-sheet for shift movement relative to the record strips including, rotatable, parallel, guide-rods supported by said frame, one at each side of the record strips, transfer-sheet holding cores rotatable with said rods, one shiftably mounted on each of said rods, a core shifting yoke slidably mounted on each of said rods, and a shifter bar to which each of said yokes is connected for being simultaneously shifted, said rods being removably connected to said frame, and said yokes being removably mounted on said rods, printing mechanism shiftable parallel to the shift of said transfer-sheet, and a shift-limiting stop adjustably mounted in the path of shift of said printing mechanism.

23. In a typewriting machine, in combination, a stationary frame, a platen over which superposed record strips are adapted to lie in position for inscription, devices for supporting a transfer-sheet for shift movement relative to the record strips including, rotatable, parallel, guide-rods supported by said frame, one at each side of the record strips, transfer-sheet holding cores rotatable with said rods, one shiftably mounted on each side of said rods, a core shifting yoke slidably mounted on each of said rods, a shifter bar to which each of said yokes is connected for being simultaneously shifted, said rods being removably connected to said frame, and said yokes being removably mounted on said rods, printing mechanism shiftable parallel to the shift of said transfer-sheet, and a shift-limiting stop in the path of movement of said yokes.

24. In a typewriting machine, in combination, a stationary frame, a platen over which superposed record strips are adapted to lie in position for inscription, devices for supporting a transfer-sheet for shift movement relative to the record strips including, rotat-

able, parallel, guide-rods supported by said frame, one at each side of the record strips, transfer-sheet holding cores rotatable with said rods, one shiftably mounted on each of said rods, core-shifting yokes, one slidably mounted on each of said rods, and a shifter bar to which each of said yokes is connected for being simultaneously shifted, said rods being removably connected to said frame, and said yokes being removably mounted on said rods, and said cores being detachable from said yokes.

25. In a machine of the character described, in combination, printing mechanism shiftable in line spacing and in letter spacing directions, a platen, a transfer sheet extending across said platen, a transfer sheet supporting frame reciprocally shiftable longitudinally of said platen and relative to said printing mechanism, and means adapted operatively to connect said sheet with said frame at opposite sides of said platen, so that said sheet shifts with said frame in each direction while remaining in substantially flat manifolding condition.

In testimony whereof I affix my signature.
EDWARD KIRBY BOTTLE.
